UNITED STATES PATENT OFFICE.

MAURICE M. MANN, OF AUSTIN, INDIANA.

SHOE-SHINING STAND.

1,382,108.

Specification of Letters Patent. Patented June 21, 1921.

Application filed January 17, 1921. Serial No. 437,889.

To all whom it may concern:

Be it known that I, MAURICE M. MANN, a citizen of the United States, residing at Austin, in the county of Scott and State of Indiana, have invented certain new and useful Improvements in Shoe-Shining Stands, of which the following is a specification.

This invention relates to shoe shining stands and is an improvement over the structure shown in my former application filed October 4, 1920, Serial Number 414,521.

The prime feature of the present invention is the provision of a sliding toe plate which may be moved lengthwise to accommodate shoes of any size, means being provided for normally holding the toe plate for the reception of a smaller shoe, and which will move forwardly to accommodate a larger shoe when pressure is applied thereto.

A further feature of the invention is the provision of expandible members for engagement with the edges of the sole of the shoe for holding the shoe in proper alignment with the stand and also for receiving pressure from the shoe for moving the toe plate forwardly.

A further feature of the invention is the provision of means for removably attaching the toe and heel engaging spurs or clamps so that if they should become bent or broken they may be readily replaced.

Other objects and advantages will be hereinafter more fully set forth and pointed out in the accompanying specification.

In the accompanying drawings, which are made a part of this application,

Figure 1 is a top plan view of the stand,

Fig. 2 is a side elevation thereof,

Fig. 3 is a transverse sectional view of the toe portion of the stand, as seen on line 3—3 Fig. 1, and

Fig. 4 is a detail sectional view as seen on line 4—4 Fig. 1.

Referring to the drawings, 1 indicates a standard which may be constructed in any suitable manner to the upper end of which is attached a platform 2, said platform being secured to the standard in any suitable manner. Mounted upon the rear end of the platform 2, as by means of a bracket 3, is a plate 4 which extends longitudinally a distance above the platform 2 and has its forward end extended through a slot 5 in a toe receiving plate 6, the rear end of said toe plate having a tongue 7 which projects a distance rearwardly below the plate 4. The

tongue 7 has a longitudinal slot 8 therethrough through which extends a rivet 9 depending from the plate 4, said rivet limiting the longitudinal outward movement of the toe plate and holding the rear end thereof in alinement with the plate 4.

The toe plate 6 is guided over the platform 2 by extending a substantially U-shaped clip 10 downwardly from the under face of the toe plate 6, the upper ends of the clip being secured to the toe plate in any suitable manner while the horizontal bar 11 thereof passes beneath a guide bar 12 secured at its ends to the forward end of the platform 2 and in spaced relation to said platform, the width of the bar 12 being substantially the same as the length of the bar 11. By mounting the toe plate in this manner it will have free longitudinal movement, but will be held in proper alinement with the platform 2 and plate 4. The toe plate 6 is normally held in position to receive the smaller size shoes by means of springs 13 at each edge of the plate 4 and between said plates and platform 2, the forward ends of the springs 13 being secured to the side edges of the clip 10 while the rear ends of the springs are secured to the bracket 3. This leaves the toe plate in condition to move forwardly for lengthening the stand when forward pressure is directed against the toe plate and will be immediately returned to its initial position as soon as the foot is removed from the toe plate.

Mounted below the platform 6 and the forward end of the plate 4 is a pair of arms 14, the inner ends of which are pivoted together while the forward ends thereof are curved outwardly away from each other and project beyond the side edges of the toe plate 6, the curved portions having slots 15 for the reception of pins 16 depending from the toe plate 6, the length of the slots 15 determining the spreading or separating movement of the arms 14. The arms 14 are normally held in contracted position through the medium of a spring 17, the forward end of the spring being attached to the arms 14 at their pivoted end while the opposite end thereof is connected with a hook 18 which engages the rear end of the tongue 7 of the toe plate.

The ends of the arms 14 projecting beyond the edges of the toe plate 6 are preferably provided with square openings 19 through which the squared portions 20 of the toe engaging spurs 21 are extended, the spurs be-

ing secured to the ends of the arms by means of nuts 22 which are turned onto the threaded lower ends of the spurs. The upper ends of the spurs 21 project above the 5 toe plate 6 and are adapted to engage the edges of the soles of the shoe, and if preferred the upper ends of said spurs may be provided with an inwardly extending lip 23 which serves to hold the sole of the shoe 10 from moving upwardly after the sole is engaged with the spurs. The heel portion of the plate 4 is also provided with spurs 24 which are secured to the plate 4 in the same manner as the spurs 21 are secured to the 15 arms 14. Consequently, should said spurs become bent or broken they may be readily replaced, and by forming the spurs substantially triangular shape in cross section, with one pointed edge in position to engage with 20 the parts of the shoe, a brush can be readily introduced around the spurs so as to cover all parts of the shoe with the shining fluid.

When applying this invention to use, the toe of the shoe is entered between the spurs 21 on the arms 14 and pushed forwardly 25 until the heel of the shoe passes in front of the spurs 24, the overhanging lips 23 holding the toe portion of the shoe in position on the stand, while the tension of the springs 30 13 will tend to draw the heel portion of the shoe against the spurs 24 with sufficient force to hold the heel stationary. In case the length of the shoe is such that the natural spread of the arms 14 will not permit the 35 heel of the shoe to pass forwardly of the spurs 24, continued forward pressure is exerted on the foot which, when the pins 16 have reached the inner ends of the slots 15, will move the toe plate 6 forwardly thereby 40 lengthening the stand and permitting the shoe heel to be lowered for engagement with the spurs 24. The tension of the springs 17 will serve to securely clamp the spurs 21 against the edges of the shoe sole thereby 45 holding the shoe against undue lateral movement even though the arms are not extended to their fullest extent.

By constructing the stand in the manner herein shown the various parts of the stand 50 will automatically adjust themselves for accommodating shoes of all sizes and will serve to hold a small shoe in position as well

as a large one. Furthermore, the parts of the device will expand automatically for receiving a larger shoe by merely direct pressure of the foot against the movable parts of the stand. 55

Having thus fully described my said invention, what I claim as new and desire to secure by Letters Patent, is:

1. In a shoe shining stand, a supporting standard, a platform attached thereto, a plate in a plane above the platform, means for rigidly connecting the plate to the platform, a toe plate slidably mounted on the 65 fixed plate, means for holding the toe plate in alinement with the fixed plate and platform, springs for retracting said toe plate, and spring controlled expansible arms for engagement with parts of a shoe when 70 placed on said stand.

2. A shoe shining stand comprising a standard, a platform fixed to said standard, a plate supported above said platform, a toe plate having a slot therethrough, through 75 which said plate extends, means for slidably mounting the toe plate on the platform, a pair of springs, one at each edge of said platform for holding the toe plate normally at its innermost position, a pair of arms co- 80 operating with said toe plate and hinged together at one end, a spring for normally holding said arms in proximity to each other, and spurs positioned in the opposite end of each arm for engagement with parts of a 85 shoe when positioned on said stand.

3. In a shoe shining stand, a stationary platform, a plate fixed to said platform, a toe plate slidable on said first mentioned plate, a clip secured to the under face of said toe plate, a guide bar carried by the platform and passing through said clip for holding the toe plate in alinement, and springs for normally holding the toe plate at its 90 innermost position.

In witness whereof I have hereunto set my hand and seal at Indianapolis, Indiana, this 13th day of January, A. D. nineteen hundred and twenty-one.

MAURICE M. MANN. [L. S.]
